UNITED STATES PATENT OFFICE.

JAMES BENTON SCHAUB, OF EVANSTON, ILLINOIS.

HOISTING CONVEYER.

Application filed November 15, 1920. Serial No. 424,130.

To all whom it may concern:

Be it known that I, JAMES BENTON SCHAUB, a citizen of the United States, and a resident of the city of Evanston, in the county of Cook and State of Illinois, have invented certain new and useful Improvements in a Hoisting Conveyer; and I do hereby declare that the following is a full, clear, and exact description of the same, reference being had to the accompanying drawings, and to the numerals of reference marked thereon, which form a part of this specification.

My invention relates to a conveyer primarily designed for handling cinders, but susceptible of conveying any other material that is desired to convey from some point to a dumping pit or a car and dump the same.

In the past these conveyers have been constructed to operate over inclines necessitating a large area of ground for their installation. In other cases, elevators have been used. In both instances, the conveying car cannot be readily dumped or emptied and much time is consumed. To overcome these objections, I have devised a tower that is perpendicular, thus occupying very little space, and allowing the cinder dumping car to serve a much wider area, making it possible to serve several lines of railroad track, where only one could be served before. Further, I have provided a structure that automatically dumps the conveyer car in a very simple way, and have provided a very compact and serviceable arrangement that saves much time, labor and expense.

It is therefore an object of my invention to provide a structure that covers but little area that automatically dumps the conveyer car in a novel way, that is quickly and readily operable and that possesses many advantages over prior structures as will become more apparent in the following description and disclosures in the drawing.

My invention is disclosed in the accompanying drawings and hereinafter more fully described and pointed out in the appended claims.

In the drawings:

Figure 1 is a central and vertical sectional view through my conveying apparatus showing the conveyer car in position under an engine to receive the cinders, and a cinder receiving car.

Figure 2 is a section on the line 2—2 of Figure 1.

Figure 3 is a fragmentary section showing the arrangement of the track, on an enlarged scale over the showing in Figure 2.

Figure 4 is a section on the line 4—4 of Figure 1, showing in plan view an arrangement of railroad tracks.

Figure 5 is a side elevation of an operating mechanism that may be used in connection with my apparatus.

Figure 6 is a top plan view of Figure 5.

Figure 7 shows a scheme for operating a reversing motor.

Figure 8 is a ground section somewhat similar to Figure 1 but illustrating a slight modification.

As shown on the drawings:

In the different figures of the drawing, similar features are denoted by similar reference numerals.

For the purpose of illustrating my invention, I have shown a plat which might consist of a part of a railroad yard having a plurality of pairs of tracks 1 and 2 over which engines can be drawn above a cinder pit or runway 3, or the like, in order to have the ashes and cinders removed therefrom. The numeral 4 represents such an engine in position to have its cinders removed. My invention comprises a specially constructed conveyer car 5, adapted to pass under the engine to receive the ashes and cinders, and a novel form of track arrangement over which said car can be hauled and elevated and dumped into a gondola car 6, such as illustrated adjacent the tower in Figure 1, and an endless traveling device attached to said car for hauling the same.

It is obvious that my invention is susceptible of being used to haul, elevate and dump any material or cargo into a car or receptacle and that any mechanic can adapt it for a particular purpose or use consistent with the description thereof. In the present instance in which my invention is shown as adapted for hauling and dumping cinders removed from railway engines, a sunken runway 3 built of concrete or the like and leading under the car is provided. The runway 3 also leads adjacent the receiving car or dumping pit, at which point a hoisting tower is provided which can be constructed in any suitable manner such as by spaced

channel members 6 (see Fig. 4) which are properly braced and connected together by struts 7 and braces 8, or the like, to provide a rigid tower of such dimensions as to freely allow the car 5 to be rolled or elevated thereup. The construction of the tower is immaterial. It should, however, be designed with reference to the tracks it has to support and the work and functions it has to perform. Accordingly, I have so designed the frame work of the tower so that a pair of vertically arranged main tracks 9 which may be in the form of angle bars can be directly attached to these channel members 6 which are nearest the dumping pit or car. The tracks 9 preferably extend from the top of the runway to approximately the top of the tower and are secured in place in any approved manner.

20 Co-operating with the tracks 9 to support and guide the conveyer car is a second pair of vertically arranged main tracks 10, which likewise may consist of angle bars attached to the struts 8 or frame work. The height 25 of these tracks 10 are so designed as to afford a convenient dumping point from the side of the tower, and are provided at their upper ends with curved guiding or transfer portions 11.

30 These curved portions 11 are termed guiding or transfer portions since they guide the conveyer car outwardly at that point and transfer it to a pair of auxiliary or dumping tracks 12 (only one of which is shown) 35 attached to the tower and projecting beyond the dumping side thereof to provide a dumping platform at a predetermined point properly located below the operating mechanism. These auxiliary tracks are of curved formation 40 corresponding to the curved portions 11 and are spaced from the curved portion an amount equal to approximately the diameter of a wheel of the conveyer car. It should be noted at this point that Figure 1 shows 45 the far side of the tower, and that the tracks 9 and 10 are spaced on a diagonal line, the track 10 being further inward and further forward toward the receiving side of the tower, and as the tracks 9 support the 50 rear wheels of the car which are mounted on an extended axle, as shown in Figure 3, it is necessary to provide a way 13 through the tracks 11 and 12 for the axle during the 55 tilting movements of the car. It will be understood that the tower is symmetrical and that the near side has the same construction and tracks as the illustrated far side.

60 The runway 3 is provided with a pair of lower horizontal main tracks 14 (see Figures 2 and 3) which are preferably built in the walls of the runway which may consist of concrete. The tracks as shown consist of similar Z bars set in the concrete. 65 These tracks extend from the pit or under

the engines to the tower where they are bent or curved upwardly and merge with the tracks 9.

Above the tracks 14, there is a second pair of horizontal main tracks 15 similar to the 70 tracks 14 but located in the wall at a point inward from the tracks 14. The tracks 14 and 15 bear the same relation to each other in respect to the spacing thereof as the tracks 9 and 10. The tracks 15 also extend 75 to the tower and are bent or curved upwardly at 16 as the tracks 14, but they are not joined to the tracks 10. Instead the curved or bent ends are spaced from the lower ends of the track 10 an amount equal 80 to substantially the diameter of a wheel of the car 5, and the lower ends of the tracks 10 are correspondingly bent as shown in Figure 1. These lower bent or curved portions 85 guide the car upwardly and the curved ends 16 also serve to transfer the car or wheels to the tracks 10 as is obvious.

The system of tracks is so constructed that the continuous or main tracks comprising the horizontal portions 14 and vertical 90 portions 9 support the rear wheels 17 which are journalled upon the extended axle 18, and the tracks 15, 10 and 12 support the side wheels 19 which are mounted on trunnions 20 supported in the side walls of the 95 car substantially near the center point thereof.

For the purpose of operating the conveyer car 5, I have illustrated endless members 21 which may consist of chains or the like trained over pulleys 22 at the far end of the runway. The endless members are secured to the rear axle 18 on opposite sides of the car, as by bolt pins 23 projecting from opposite sides of supports 24 rigidly 105 secured to the axle. The endless members 21 extend in the runway to the tower where guide pulleys or rollers 25 are provided to properly direct the endless members vertically up the tower where they are trained 110 over sprocket wheels 26 keyed on a shaft 27 supported in a housing 28 near the top of the tower and above the dumping point or in any other convenient place. The housing may be supported by means of channels secured around the tower and the shaft 27 may be journalled in bearings supported by I beams resting upon the channels. The shaft 27 is contemplated to be driven by a motor 29, gears 30 and 31 and the worm 115 bearing 32 driven by a worm on shaft 33. In order to stop and reverse the drive at the upper and lower limits of travel of the conveyer car 5, it is contemplated that a reversing motor be used. The motor 125 may be reversed by means of a screw shaft 34 (see Figure 7) operated by the main shaft 27 by gearing and having a traveling nut 35 which has a finger or projection 36 to shift a switch or 130

65

the like. The arrangement should be such that the switch will be operated and the motor reversed at the limits of travel of the car 5. I have not shown the details 5 of the switch and the reversing motor as the same do not constitute part of my invention since they are well known. My invention merely contemplates the use of some means for driving the endless members and 10 for stopping and reversing the drive at the limits of travel.

The construction of the conveyer car 5 which receives the cinders or cargo to be carried thereby may be varied. Thus in 15 Figure 1, I have shown a car having an open front end which slopes downwardly and a portion of the top of the car is open to receive the cinders or material to be carried, and in Figure 8 I have shown a car 20 having merely an opening in the top to receive the material, the front end being closed by a door 34 hinged at its upper end but maintained in a closed position by means of an arm 35 secured thereto and having a 25 roller or spherical head 36 riding directly under a member 37. Thus the door will be held closed until the car assumes an upwardly tilted or vertical position when the pressure on the door is released.

30 The operation is as follows:

As the operation of the car is controlled by the motor, it is only necessary for the operator to control the current. Assuming now that the car is in the illustrated position and has been filled with cinders, which 35 have been shoveled from the engine through the hopper 38, if the current is turned on, the endless members will travel around the sprocket wheels which are rotated by the 40 aforescribed gearing. The car will hence be drawn to the tower on the tracks 14 and 15 ascending the curved or bent portions, the bent portions 16 guiding and transferring the center side wheels 19 to the tracks

45 10. As the car wheels 19 reach the guiding and transfer portions 11, they will be transferred to the auxiliary tracks 12 and guided outwardly as is obvious, the axle 18 passing through the passages 13, as the endless members 50 raise the rear end of the car to tilt the same. Hence the car can be said to be rolled up the hoisting tower. The car will be tilted on the side wheels which rest upon the auxiliary tracks 12 and act as pivotal fulcrums,

55 and the contents of the car will accordingly be dumped, and as the auxiliary tracks extend well beyond the side of the tower, the contents will fall clear of the tower and may be received by a gondola car such as 60 illustrated. And when the car has been fully tilted, it is contemplated that it will be stopped and reversed by the reversing motor used and be free to descend for a second load.

65 It will accordingly be observed that I

have provided a conveyer or hoist that uses a vertical tower in which the car is drawn up, in which certain tracks are provided with guiding and transfer portions to guide the car onwardly on extending auxiliary or 70 dumping tracks, giving a compact arrangement that utilizes but little space, and can hence be employed where the inclined type of conveyer is impracticable.

I am aware that numerous details of construction may be varied through a wide range without departing from the principles of this invention, and I therefore do not purpose limiting the patent granted otherwise than necessitated by the prior art. 75

I claim as my invention:

1. In an apparatus of the class described, a tower, a plurality of pairs of main tracks supported by said tower, said tracks extending up said tower, one pair of tracks having 85 curved ends, a pair of auxiliary tracks, a conveyer car, and means for drawing said car up said main tracks guided by said curved ends on to said auxiliary tracks and dumping the same. 90

2. In an apparatus of the class described, a tower, a plurality of pairs of main tracks supported by said tower, one pair of said tracks being provided with outwardly curved guiding portions at the ends thereof, a pair 95 of outwardly curved auxiliary tracks in parallel relation to said curved portions, a conveyer car, and means for drawing said car up said main track and on to said auxiliary tracks and dumping the same. 100

3. In an apparatus of the class described, a tower, main tracks supported on said tower, curved auxiliary tracks extending from said tower, a conveyer car, and means for drawing said car up said main tracks, 105 and curved guiding means co-operating with said auxiliary track for transferring said car from said main tracks to said auxiliary tracks.

4. In an apparatus of the class described, 110 a tower, main tracks extending up said tower, curved auxiliary tracks extending outwardly from said tower, a conveyer having lateral wheels arranged intermediate of the ends thereof, and means for drawing 115 said car up said main tracks and transferring the same to said auxiliary tracks and automatically tilting the same on said lateral wheels as fulcrums.

5. In an apparatus of the class described, 120 a tower, vertical tracks extending up said tower, horizontal tracks leading to said tower and provided with upwardly curved transfer ends adapted for transferring a car from said horizontal tracks to said vertical tracks, curved auxiliary tracks extending laterally from said tower, a conveyer car having lateral fulcrum wheels intermediate the ends thereof, and means for drawing said car over said horizontal tracks, 125 130

up said vertical tracks and onto said auxiliary tracks and automatically tilting the same on said fulcra wheels for dumping purposes.

5 6. In an apparatus of the class described, a tower, two pairs of spaced tracks extending up said tower, one pair of said tracks having curved transfer portions, a curved auxiliary track extending from said tower 10 and having a portion in parallel spaced relation with said transfer portion of one pair of main tracks, a conveyer car having rear wheels and lateral fulcra wheels intermediate the ends thereof, and means for drawing 15 said car up said tracks and on to said auxiliary tracks with the lateral wheels passing between the curved portions of said tracks.

7. In an apparatus of the class described, a tower, vertical tracks leading up said 20 tower, curved auxiliary tracks leading from said tower and co-operatively arranged with said vertical tracks for receiving a car therefrom, a dumping car having lateral fulcra wheels substantially centrally ar-

ranged, and means for drawing said car up 25 said vertical tracks and onto said auxiliary tracks and automatically dumping the same on said fulcra wheels.

8. In an apparatus of the class described, a tower, a system of tracks extending up 30 said tower, a curved auxiliary track extending from said tower and cooperatively arranged with said system of tracks for having a car transferred thereto from said system, a conveyer car having a rear axle with 35 wheels thereon and intermediate lateral fulcra wheels, and means engaging the rear axle for drawing said car up said system of tracks and onto said auxiliary track and automatically dumping the same with said 40 lateral wheels as fulcra.

In testimony whereof I have hereunto subscribed my name in the presence of two subscribing witnesses.

JAMES BENTON SCHAUB.
